CHANGEABLE EXHIBITOR

Lee Grossman, Los Angeles, Calif.

Application May 9, 1945, Serial No. 592,785

6 Claims. (Cl. 40—65)

1

This invention relates generally to the class of signals and indicators and pertains particularly to an indicator designed for use in connection with games for designating certain periods of play.

A principal object of the present invention is to provide a device designed primarily for use in the playing of football, to designate the downs, the device being constructed and arranged in a novel manner whereby it may be easily and quickly moved around from place to place in the field and, by the manipulation of certain control levers by the person attending upon the device, specific units of the device may be selectively displayed to indicate whether there is a first, second, third or fourth down.

More specifically the invention broadly contemplates the provision of a plurality of hollow signal units or boxes, two of which are fixed together against relative movement and are mounted upon a supporting pole or standard one partially within and above the other, with three intermediate telescopically arranged boxes disposed between the first two and designed to be selectively extended by means of control levers, from the lower and outer fixed box upwardly around the upper and inner fixed box, the said upper fixed box and the three relatively movable boxes carrying upon their several sides the "down" designating numerals. For example, the inner fixed signal box carries upon each of its sides the numeral "1." The next larger and outer box which is movable upwardly around the inner fixed box, carries upon each of its sides the numeral "2." The third movable box carries the numeral "3" upon each of its sides and the fourth movable box carries the numeral "4" upon each of its sides. When all of the movable boxes are lowered within the lower fixed signal box they will be completely hidden and only the numeral "1," designating the first "down," will be visible upon the upper fixed box. The lower fixed signal box will have each of its sides marked with the word "down."

The invention will be best understood from a consideration of the following detailed description taken in connection with the accompanying drawings forming a part of this specification, with the understanding, however, that the invention is not confined to a strict conformity with the showing of the drawings but may be changed or modified so long as such changes or modifications mark no material departure from the salient features of the invention as expressed in the appended claims.

2

In the drawings:

Figure 1 is a view in side elevation of the exhibitor constituting the present invention.

Figure 2 is a vertical sectional view through 5 the top part only of the exhibitor showing one of the boxes partly raised.

Figure 3 is a transverse section taken on the line 3—3 of Figure 1.

Figure 4 is a fragmentary section taken on the 10 line 4—4 of Figure 3.

Figure 5 is a view in perspective of the top part of the exhibitor showing the three movable boxes in different stages of elevation.

Figure 6 is a partial vertical section taken on 15 the line 6—6 of Figure 2.

Figure 7 is a partial vertical section taken on the line 7—7 of Figure 1.

Figure 8 is a section taken transversely of the 20 standard and showing in full and dotted lines the two positions which may be assumed by an actuating lever in the raised position.

Figure 9 is a sectional view taken on the line 9—9 of Figure 8.

Referring now more particularly to the drawings wherein like numerals of reference designate 25 corresponding parts throughout the several views, the numeral 10 generally designates the supporting pole or standard for the signal device, the lower end of which pole is preferably pointed 30 as indicated at 11 for easy penetration of the turf so that the device may be readily maintained in upright position.

Upon the upper end of the pole is fixed the 35 base plate 12 upon which the hereinafter described signal boxes are supported. This plate, together with the boxes supported thereby, is preferably square in outline and it is defined at its outer edge by the upstanding flange 13 while at its center it has formed the integral sleeve 14 which extends down into the pole 10, which is 40 of hollow form, where it is secured in any suitable manner as by welding or the like.

Supported upon the plate 12 is the relatively 45 long vertically disposed fixed outer box which is generally designated 15 and which is of square cross section, the bottom part of the box being fitted over the flange 13 of the bottom plate and secured thereto by the screws 16 or in any other suitable manner. The top end of the box 15 is 50 open and each of the four sides 17 has printed or otherwise formed thereon the word "down." It is preferred that the coloring of the letters contrast strongly with the background of the wall 17 upon which the word is printed so that it may be 55 readily seen or read from a distance. The letters

may be of luminous character so as to clearly show up when used at night games.

Supported upon the plate 12 and extending upwardly through the outer fixed box 15 and to a distance above the box substantially equal to the height of the box, are the two fixed channel standards 18. These are disposed at opposite sides of the center of the base plate with the channel sides in opposed relation and at their lower ends they have the laterally turned ears 19 which rest upon the top of the base plate and are riveted thereto while at their upper ends they are connected by the cross braces 20.

Enclosing the channel standards is the inner fixed signal box 21 which is of square cross section and upon the outer face of each of the side walls 22 of which is printed the numeral "1."

The fixed signal box 21 is of a width materially less than the fixed box 15 in which it is centrally located so that a considerable space is left between the four sides of the two fixed boxes and more particularly between the outer sides of the channel standards and the adjacent walls of the fixed box 15, since the fixed inner and upper box 21 is secured to the tops of the standards 18 as shown and only has a small portion of its lower end lying within the lower fixed box 15. The upper fixed box 21 is of a height substantially equal to the height of the lower box and when viewed from the side the upper fixed box appears to be a smaller extension upwardly of the lower box.

Enclosed within the lower fixed box 15 and nested in the area between the two boxes are the three shiftable boxes which are designated 23, 24 and 25.

The innermost one of the three shiftable boxes, that is, the box 23, has the numeral "2" upon each of its four sides while the next outer box 24 has the numeral "3" upon each of its four sides and the last outer movable box has the numeral "4" upon each of its four sides.

Extending across the lower end of each of the boxes 23, 24 and 25, is a bar 26. These bars are arranged in different vertical planes within the structure as shown in Figure 4 and they are of different lengths corresponding with the width of the lower end of the box in which each bar is fitted.

Each lifting bar 26 terminates at each end in the spaced arms 27 and the ends of these arms position against the inner sides of the box to which the bar is attached and are formed to receive securing screws 28 which pass through the sides of the box.

It will be readily apparent from the foregoing that the longer one of the lifting bars 26 will be disposed in the lower end of the outer movable box 25, the next longest lifting bar 26 being within the lower end of the intermediate movable box 24 and the shorter lifting bar 26 being within the lower end of the inner movable box 23. Thus the inner box 23 may be raised, or lowered, independently of the boxes 24 and 25 and when it is in raised position, the next box 24 may also be raised to cover the box 23 and lastly, when the two boxes 23 and 24 are raised, the outermost box 25 may be raised to cover the box 24.

When the boxes 23, 24 and 25 are lowered within the lower fixed box 15 they will be completely housed therein and the lower edge of the intermediate box 24 may rest upon the crossbar 26 of the outer box 25 while the lower edge of the inner movable box 23 may rest upon the

crossbar 26 which is attached to the lower end of the intermediate box 24.

The crossbars 26 each has a suitable opening formed therein as indicated at 29, midway between its ends and fastened in such opening is an end of a lifting rod 30 which extends downwardly into the tubular pole or standard 10.

The rods 30 are of different length and each is attached at its lower end to a circular terminal block 31 which is located within the tubular standard or pole 10.

The blocks 31 are three in number, corresponding to the number of rods 30 and they are arranged one above the other within the pole. The uppermost one of the blocks 31 has attached thereto the lower end of that rod 30 which is coupled with the innermost movable box 23. The rod 30 attached to the intermediate movable box 24 extends freely through an opening in the upper block 31 to and is secured in the next lower or intermediate block 31 while the third rod 30, which is attached to the outer movable box 25 passes through openings in both the uppermost and intermediate blocks and is secured to the lowermost block 31, as illustrated in Figure 7.

Each of the blocks preferably has a depending skirt portion 31' integral therewith which has contact with the wall of the standard 10 and serves to maintain the block in proper position.

It will be readily obvious from the foregoing that the uppermost block may be shifted vertically when desired to lift the innermost or numeral "2" bearing box 23, the block sliding upwardly freely on the other two rods. Likewise the intermediate and lower box may be lifted when desired. The means for affecting the lifting of the blocks 31 and the boxes connected thereto through the medium of the rods 30, comprises a lever arm 32 for each block 31, which extends through a guide slot 33 formed in the wall of the tubular pole and at its inner end is secured in the top of the block which it is employed to shift. These levers 32 are in a common vertical plane, when the blocks and the attached movable boxes are in fully lowered position but each lever is turned downwardly at its inner end, where it connects with the block, to form a pivot 34 by which it may be oscillated, transversely of the pole 10, to facilitate the proper positioning of the levers when assembling the parts in the standard.

In order to facilitate the movement of the three movable boxes and the maintenance of the same in the proper spaced relation, guide or track forming angle bars 37 are secured along certain 55 of the corners of each of the movable boxes and of the upper or central fixed box as shown in Figures 3 and 5.

The upper ends of the boxes are covered by the plate member 38 which overlies and is secured to the top of the central fixed box member 21, as shown most particularly in Figure 6.

In the use of the present "down marker," the same is maintained in vertical position at the desired location on the playing field and at the start of play all of the handle levers 32 will be in lowered position, as shown in Figure 1, so that the movable boxes 23, 24 and 25 will be housed within the lower fixed box or casing 15 and thus hidden entirely from view. There will then be displayed to the spectators of the game in association with which the device is used, the word "down," which is maintained on view at all times, and the numeral "1." At the completion of play, when a second down is to be designated, the attendant of the device raises the uppermost handle

lever 32 to the top position. This raises the innermost movable box 23 which covers the central or fixed box 21 and exposes the numeral "2" to the spectators. The next or intermediate movable box may then be shifted upwardly in the same manner at the proper time and when the fourth down comes up, the last movable box, designated 25, may be shifted upwardly and maintained in place. After the four downs have been had or played the handle levers 32 are all shifted back down in the slot 33 and the movable boxes thus allowed to return in nested relation within the casing box 15.

I claim:

1. An exhibitor of the character described, comprising a pair of bodies of substantially equal length, one of the bodies having a materially greater girth than the other, means maintaining the bodies in a fixed relation and on a common longitudinal axis, the body of greater girth being hollow and open at one end, the other body being arranged with its major portion disposed outside the hollow body at the open end thereof, the bodies being arranged vertically for use with the body of greater girth below the other body, a hollow box-like body having a girth intermediate the girths of the pair of bodies and encircling the said other body and freely movable longitudinally thereof into and out of the body of greater girth, the bodies being designed to bear exhibition material upon their sides, and means for moving the box-like body into and out of the body of greater girth, into and out of encasing relation with the body of smaller girth.

2. An exhibitor of the character in claim 1, with a supporting standard attached at one end to the lower end of the body of greatest girth, the said means for moving the box-like body including a rod attached to the box-like body and extending downwardly in parallel relation with the standard, a lever connected with said rod forming a handle for the manipulation of the rod, and means for coupling the lever with the standard when the box-like body has been moved by the rod into encircling relation with the said other body.

3. An exhibitor of the character described in claim 1, with a tubular standard connected at one end with the lower end of the body of greatest girth, the said means for moving the box-like body including an actuating rod connected at one end with the box-like body and extending downwardly into the tubular standard, a tubular standard having a longitudinally extending wall slot, a handle lever connected with the other end of the rod and extending through said slot and adapted to move longitudinally therein, and means for securing the handle lever to the standard when the lever has been moved to a position in the slot in which the box-like body is in encircling relation with the said other body.

4. An exhibitor of the character described, comprising a pair of bodies of substantially equal length, one of the bodies having a materially

greater girth than the other, means maintaining the bodies in a fixed relation and on a common longitudinal axis, the body of greater girth being hollow and open at one end thereof, the bodies being arranged vertically for use with the body of greater girth below the other body, a plurality of hollow box-like bodies arranged in nested relation in the body of greatest girth and outside the said other body, means comprising a

5 10 15 20 25 30 35 40 45 50 55 60

tubular standard for supporting the bodies, said bodies being designed to bear exhibition material upon their sides, means for shifting each of said nested box-like bodies out of the lower body into encircling relation with the said other body, comprising a rod connected with each box-like body and extending downwardly into said tubular standard, a handle lever attached to each of said rods, said tubular standard having a longitudinal slot through which the handle levers extend, and means for securing each of said handle levers when it has been moved a predetermined distance in the slot to extend the box-like body with which it is coupled to exhibiting position outside the lower box.

5. An exhibitor of the character stated, comprising a hollow body of substantial length and open at one end, a standard connected with the other end of the body to support the same vertically, a frame structure secured to the hollow body and extending upwardly from the interior thereof to a substantial height above the open upper end, a box-like body of substantial length carried by the frame structure above the open upper end of the hollow body, in vertical position and coaxial with the hollow body, said box-like body being fixed to the standard and having a girth materially less than the hollow body, a plurality of hollow box-like bodies arranged in nested relation in the hollow body and adapted for extension through the open top thereof into encasing relation with the fixed box-like body, the said bodies being designed to have exhibition material upon the outer sides thereof, and means connected with the said nested box-like bodies and operable from a position below the hollow body for effecting the individual extension of the nested bodies into encasing relation with the fixed body.

6. An exhibitor of the character stated in claim 5, in which said standard is of tubular form, the said means for shifting the nested bodies comprising a rod connected at one end with each nested body and extending downwardly into the tubular standard, a lever handle connected with each rod, the tubular standard having a longitudinal slot through which the lever handles extend to their respective rods, and means for coupling each lever handle with the tubular standard when the lever handle has been shifted to a predetermined position in the slot for the extension of the box-like body coupled therewith to exhibiting position.

LEE GROSSMAN.
